UNITED STATES PATENT OFFICE.

JOHN HOPSON, JR., AND LEWIS S. DANIELS, OF NEW LONDON, CONNECTICUT.

SECTIONAL BOILER.

SPECIFICATION forming part of Letters Patent No. 358,449, dated March 1, 1887.

Application filed May 12, 1886. Serial No. 202,010. (No model.)

To all whom it may concern:

Be it known that we, JOHN HOPSON, Jr., and LEWIS S. DANIELS, citizens of the United States, and residents of New London, in the county of New London and State of Connecticut, have jointly invented certain new and useful Improvements in Cast-Iron Sectional Boilers, of which the following is a full, clear, and exact description, reference being had to the accompanying drawings, and to the letters of reference marked thereon.

Our invention relates to that class of boilers in which the vertical sections are so constructed and arranged as to take upon their exterior and around the fire-box a general circular or oval form, the inner surfaces above the fire-box affording space to admit a self-feeding coal-magazine, and leaving passages for the escape of products of combustion, and each section connected at top and bottom with circulating pipes or headers.

The objects of our invention are, first, to so construct and arrange the various sections and their connections that they may freely expand and contract; second, to locate the lower header below the point of support for the various sections; third, to support the lower header by connections with the supported sections and the grate upon the lower header; and, fourth, to provide simple and efficient means for holding the packing between the boiler-sections. To accomplish these objects our improvements involve certain new and useful peculiarities of construction, relative arrangements or combinations of parts, and principles of operation, all of which will be herein first fully described, and then pointed out in the claims.

In the accompanying drawings, forming part of this specification, Figure 1 is a vertical section and elevation of a boiler embodying our improvements, the exterior shell or casing, smoke-pipe, and base or ash-pit section being omitted as being unnecessary for purposes of the present description. Fig. 2 is a view in horizontal section, the part to the right indicating the form of the boiler-sections at the region of the fire-box and the part to the left showing the projections above the fire-box. Fig. 3 is a plan view of the lower header detached from the other parts, showing the lugs for receiving the arms upon the grate-ring.

In all these figures like letters of reference,

wherever they occur, indicate corresponding parts.

A is the top header, with which the various boiler-sections are connected; B, the self feeding coal-magazine, and C C' C² the hollow boiler-sections.

D D are the packing-strips; E, the packing-strip lock; F, the catch formed on the outer surface of the sections; G, dovetails or lugs formed on the lower header to receive the arms of the grate-ring; H, the lower header; I, the boiler supporting ring, and J the grate-ring.

The top header, A, is used to connect the several boiler-sections at top and hold them firmly and properly in place, and constitutes the top of the boiler, its central open part admitting the self-feeding coal-magazine B, which is sustained upon the header. The space between this header and the boiler-sections, accommodating the nipples a a, used to make the necessary connections, forms a passage for the escape of the products of combustion.

The boiler-sections shown at C surround the fire-box and are varied in form, as shown at C', to fit above the fire-door, and at C² to fit below it. Above the fire-box the sections project over it, as shown at the left of Fig. 2. While the sections, when assembled, are intended to form a closed interior, the joints between them will not ordinarily be close enough to be gas-tight; and in order to make them gas-tight they are luted with suitable material, and the packing-strip D is used to cover the joint and retain the luting, and this strip is partly contained within a groove formed along each outer edge of each boiler-section, as indicated in Fig. 2. This packing-strip is held in place by the packing-strip lock E, the latter secured to the boiler within the catch formed on the outer surface of the boiler-sections, as shown at F.

The boiler-header H is used to establish connection between the several boiler-sections at bottom and to hold them in proper relative positions at that point, the connections being made by nipples, as at b, and it is also used to support the grate. On its interior are the dovetails or lugs G to receive the depending arms c, which are connected with the grate-ring J.

The boiler is supported upon a plate-ring, I, made in one or more pieces and so placed that the lower ends of the boiler-sections rest

upon it, as plainly shown. This plate-ring in practice is suitably sustained upon or by whatever form of base may be applied to the boiler. No base being shown in the drawings, the 5 darts, Fig. 1, are employed to indicate the direction of the sustaining force.

It will be observed that the lower header is located below the fire-surface and independent of the supporting-ring, and that the arrangement is such that all the sections are separately readily accessible for removal or adjustment, and that the various parts above and below the supporting-ring are free to expand or contract without disturbing each other.

15 The grate-bars *d* are sustained by the grate-ring *J*, and the latter by the lower header, as above explained. The grate-ring may be easily detached and removed at any time.

We are aware that cast-iron sectional boilers 20 containing hollow projections similar to those shown in Figs. 1 and 2 have been used prior to our invention, and are shown in patent granted to John F. Daniels, September 7, 1875, No. 167,438. We do not, therefore, claim such 25 construction, broadly; but

What we do claim as new herein, and desire to secure by Letters Patent, is—

1. In a sectional cast-iron boiler, the combination of the vertical hollow sections ar-

ranged in circular or oval form, said sections 30 being connected at top and bottom with circulating pipes or headers, the top header admitting and sustaining the fuel-magazine, and the whole supported from points in or on the lower ends of the sections and independent of 35 the lower header, substantially as shown and described.

2. The lower header or connecting-pipe, combined with the boiler-sections and sustained by and beneath them, the said sections 40 being supported upon a bearing independent of the lower header, substantially as and for the purposes set forth.

3. In combination with the lower header, 45 sustained by and beneath the vertical boiler-sections, the removable grate-ring supported upon said header, substantially as shown and described.

4. The combination, with the vertical boiler-sections, of the packing-strips for holding the 50 packing and the packing-strip lock, substantially as shown and described.

JOHN HOPSON, JR.
LEWIS S. DANIELS.
